UNITED STATES PATENT OFFICE.

EDWARD PAYSON BEADLES, OF DANVILLE, VIRGINIA.

RETURN-HOOP TOY.

1,116,786.

Specification of Letters Patent.

Patented Nov. 10, 1914.

Application filed July 28, 1914. Serial No. 853,582.

To all whom it may concern:

Be it known that I, EDWARD P. BEADLES, a citizen of the United States, residing at Danville, in the county of Pittsylvania and State of Virginia, have invented certain new and useful Improvements in Return-Hoop Toys; and I do hereby declare the following to be a full, clear, and exact description of the invention, such as will enable others skilled in the art to which it appertains to make and use the same.

My invention consists in the novel features hereinafter described, reference being had to the accompanying drawing, which shows an embodiment of the invention selected by me for purposes of illustration, and the said invention is fully disclosed in the following description and claims.

Referring to the said drawings, Figure 1 shows my improved return hoop or toy in full lines, with the elastic flexible spinning member wound around the same, and the handle held in the hand preparatory to throwing the hoop, and illustrating in dotted lines, the manner of using the toy and its operation in use. Fig. 2 is a side elevation of the hoop detached. Fig. 3 is a view showing the flexible elastic spinning member. Fig. 4 is an edge view of the hoop showing the retaining devices therein for detachably engaging one end of the spinning member. Fig. 5 is an enlarged sectional view of a portion of the hoop and spinning member showing the parts in the position which they occupy just before the hoop is thrown.

The object of my invention is to provide a toy return hoop, that is to say, an arrangement by which a light hoop can be rapidly thrown, by a child or other operator using the same to a considerable distance, a back spin being imparted to the hoop by the spinning member forming part of the toy so that when the hoop strikes the ground, or has reached the limit of its movement under the impetus of the throw, the back spin imparted to it will cause it to roll back along the ground to the operator or user so that it can be rapidly thrown and caught without the necessity of the user materially changing his position and the whole therefore constitutes a useful and amusing toy. In the embodiment of my invention herein shown, which I have selected for purposes of illustration, it comprises essentially two members, a light hoop 1 which is preferably

made of light wood or thin sheet metal or other suitable material, and is provided with a peripheral groove indicated at 2. The hoop is also provided with suitable means for retaining detachably one end of the spinning member and the retaining means are so constructed that the hoop can have the spinning member wound around it in either direction to facilitate the use of the device and obviate the necessity of placing the hoop in a particular relation with the spinning member. In the present instance these retaining devices are formed by providing the lateral flanges 3—3 of the hoop, on opposite sides of the groove 2, with pairs of recesses 4—4 and 5—5, the recesses of each pair having an undercut shoulder 4^a and 5^a, as best seen in Fig. 5, the said undercut shoulders 4^a and 5^a being inclined in opposite directions. The flexible spinning member comprises a piece of flexible, and preferably elastic material which may be in the form of a rubber cord 6, one end of which is provided with a handle 7 of any suitable construction to be easily held between the palm and the third and fourth fingers of the hand, leaving the thumb and the first and second fingers free to hold the hoop. The other end of the flexible spinning member is provided with means for engaging detachably the retaining means on the hoop, and in this instance, I have shown the flexible elastic member 6 provided with a loop 8 of wire, which is adapted to be placed in engagement with the recesses 4—4 or 5—5 and to engage the retaining shoulder 4^a or 5^a to temporarily connect the spinning member with the hoop so that it can be wound around the hoop and made to lie in the peripheral groove 2 thereof, as shown in Figs. 1 and 5.

In using the toy, the loop 8 is engaged with one set of notches or recesses, as shown in Fig. 5 and the flexible elastic member 6 is wound around the hoop, which is then held by the thumb and first two fingers, or the thumb and the first finger, while the handle 7 is firmly grasped and retained between the remaining fingers and the palm, as shown in full lines at A in Fig. 1. The operator then preferably swings his arm rearwardly, as indicated in dotted lines at B, and then forwardly, releasing the hoop but retaining hold of the handle of the spinning member. The hoop is thus thrown forward, as indicated at C, following the trajectory indicated by the dotted line c, and

in following this trajectory, a back spin indicated by the arrows c' is imparted to the hoop by the unwinding of the flexible elastic member 6, which may be assisted by the 5 longitudinal contraction of the said member, and which will also be assisted by the elastic jerk rearward, imparted to the retaining shoulder 4^a or 5^a. As soon as the elastic flexible member 6 is entirely unwound, the 10 hoop becomes entirely detached therefrom and flies onward, while rotating backward until it reaches the ground and its forward momentum is checked, as shown at D in Fig. 1 in dotted lines, whereupon the back spin 15 imparted to the hoop will cause it to rotate backward in the direction of the arrow d , Fig. 1, and will carry it back to the user or operator, as indicated at E in dotted lines. The operation can be repeated as often as 20 desired, and will afford considerable entertainment and amusement to children and others.

What I claim and desire to secure by Letters Patent is:—

25 1. A return hoop toy comprising among its members a light hoop, provided with a peripheral groove, and a flexible spinning member, of a length substantially equal to the periphery of said hoop, adapted to engage said groove, for imparting a backward spin to the hoop, and having a hand engaging portion at one end, the other end of said flexible member, and said hoop being provided with interlocking portions, whereby 30 when the said flexible member is secured to and wound around the hoop, the hand engaging portion being retained by the hand of the operator, the hoop may be thrown to considerable distance and will be returned to 35 the operator along the ground by the backward spin imparted to it by said flexible member.

40 2. A return hoop toy comprising among its members a light hoop provided with a peripheral groove, and a flexible longitudinally elastic spinning member, of a length substantially equal to the periphery of said hoop, adapted to engage said groove, for imparting a backward spin to the hoop, and 45 having a hand engaging portion at one end and a hoop engaging device at the other, the hoop being provided with means for detachably engaging said hoop engaging device, whereby when said elastic spinning member

55 is wound around the hoop and the hoop is thrown the hand engaging portion of the spinning member being retained by the hand of the operator, the hoop may be thrown to a considerable distance and will be returned to the operator along the ground by the 60 backward spin imparted to it by said flexible elastic spinning member.

65 3. A return hoop toy comprising among its members a light hoop provided with a peripheral groove, and oppositely disposed retaining members, of a flexible spinning member, of a length substantially equal to the periphery of said hoop, provided at one end with a handle, and at the other end with a retaining device for detachably engaging either of the said retaining members, to permit the spinning member to be detachably secured to one of said retaining members and wound in either direction around said hoop, whereby the hoop may be thrown to 70 a considerable distance by an operator, while retaining hold of the said handle, and the backward spin imparted to the hoop will cause it to return along the ground to the operator.

75 4. A return hoop toy comprising among its members a light hoop provided with a peripheral groove having the lateral flange portions on opposite sides of said groove, provided with two sets of notches having 80 inclined retaining shoulders, the said shoulders of one pair of notches being inclined oppositely from the shoulders of the other pair of notches, and a flexibly elastic spinning member, provided at one end with a loop to 85 detachably engage the shoulders of either pair of notches, and having a short handle secured to the other end, whereby when the said loop is detachably secured to the hoop and the spinning member is wound around 90 said hoop in either direction, and the handle retained in the hand, the hoop may be thrown a considerable distance, and will be returned along the ground to the operator by the backward spin imparted to the hoop 95 by said elastic spinning member.

In testimony whereof I affix my signature, in the presence of two witnesses.

EDWARD PAYSON BEADLES.
